UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

FEEDING MECHANISM FOR WEFT-REPLENISHING LOOMS.

1,369,474.

Specification of Letters Patent. Patented Feb. 22, 1921.

Application filed February 26, 1920. Serial No. 361,498.

To all whom it may concern:

Be it known that I, EPPA H. RYON, a citizen of the United States, residing at Waltham, in the county of Middlesex and State of Massachusetts, have invented a new and useful Feeding Mechanism for Weft-Replenishing Looms, of which the following is a specification.

This invention relates to a mechanism 10 for advancing fresh weft carriers to transfer position in a weft replenishing loom.

In weaving certain classes of goods, two shuttles are used with a single kind of weft, two picks of weft from each shuttle being 15 inserted alternately. The object of this construction is to mix the weft so that no variation may be apparent when a fresh weft carrier is inserted.

It is the object of my present invention to 20 provide mechanism by which the advance of a fresh weft carrier to transfer position may be delayed after indication of substantial weft exhaustion, so that transfer will only occur upon the return of the indicated shuttle which will be on the fourth pick after indication.

A further object of my invention is to provide mechanism of this character available to indicate approaching exhaustion of the 30 second shuttle between indication and replenishment of the first shuttle, should such substantially simultaneous exhaustion occur.

My invention further relates to arrangements and combinations of parts which will 35 be hereinafter described and more particularly pointed out in the appended claims.

A preferred form of my invention is shown in the drawings in which—

Figure 1 is a side elevation of certain 40 parts of a weft carrier magazine with my improved feeding mechanism applied thereto;

Fig. 2 is a front elevation thereof;

Figs. 3, 4, 5 and 6 are enlarged side elevations of the feeding mechanism, showing the parts in different successive positions;

Fig. 7 is a detail sectional view taken along the line 7—7 in Fig. 1, and

Fig. 8 is a partial perspective view of a part to be described.

Referring to the drawings, I have shown a frame 10 mounted on a breast beam 11 and forming a portion of a rotary magazine of well known construction. A ratchet wheel 12 is secured to the magazine and rotates therewith, certain teeth of said ratchet wheel being designated as *a*, *b*, *c*, *d* and *e* for the purposes of this description.

A holding pawl 13 is pivoted at 14 on the frame 10 and is yieldingly held in operative 60 position by a spring 15. The pawl 13 is shown in the drawings in engagement with the tooth *a* of the ratchet wheel 12.

A transerrer 16 is pivoted at 17 on the frame 10 and is preferably given a downward transferring movement on each alternate beat of the lay by a link 18 connected to actuating mechanism not shown. A rod 19 (Fig. 7) is mounted to slide transversely in the head of the transerrer 16 and is positioned by weft indicating mechanism mounted on the head of the transerrer.

A full description of suitable actuating mechanism may be found in my co-pending application, Serial No. 244,637, filed July 12, 1918, and a complete description of suitable weft detecting mechanism for positioning the rod 19 may be found in my co-pending application Serial No. 297,302, filed May 15, 1919. For the purpose of this application, it is sufficient to state that the rod 19 is moved to the left in Figs. 2 and 7 upon indication of substantial weft exhaustion.

A feed pawl 20 is pivoted at 21 on the transerrer 16 and a spring 22 is connected at one end to the pawl 20, and at the other end to a stud 23 on the transerrer 16. The normal position of the parts is shown in Fig. 1 in which the feed pawl 20 engages the tooth *c* of the ratchet wheel 12 and the holding pawl 13 engages the tooth *a*.

A shield 24 normally covers the tooth *d* immediately below the feed pawl and prevents engagement of the feed pawl therewith. The shield 24 is provided with a split bearing 25 mounted on the hub of the

magazine and frictionally engaged therewith by the pressure of a spring 26. One portion of the split bearing 25 is extended and enlarged to form a counter weight 27 for a purpose to be described. A depending arm 28 is formed integral with the shield 24 and with one portion of its bearing 25 and said arm is provided with a cam face or shoulder 29 (Fig. 8) positioned for engagement by the pin 19 when the latter is in the left-hand position shown in Fig. 7. An additional cam projection 30 is formed on the arm 28 for resetting the pin 19.

10 A second arm 31 is formed on the shield 15 24 and projects directly forward where it is upturned to engage a stud 32 on the holding pawl 13, preventing displacement of the pawl 13 when swung away from the ratchet wheel 12. The feed pawl 20 also has an upward projection 33 positioned adjacent the stud 32. This stud 32 is grasped by the operator and moved forward to withdraw both pawls 20 and 13 from the ratchet wheel 12, when the operator wishes to revolve the 25 weft carrier holder backward for replenishment. Such withdrawal movement is limited by the upturned end of the projection 31.

15 A stud 34 in the pawl 13 limits downward movement of the projection 31, while upward movement thereof is limited by the stud 32.

Having described the construction of my 30 improved feeding mechanism, I will now describe its operation. The normal position of the parts is shown in Fig. 1 in which the holding pawl 13 engages the tooth *a* of the ratchet wheel and the feed pawl is at the upper limit of its stroke and engages the 35 tooth *c* of the ratchet wheel. A weft carrier *W* in the shuttle is positioned for engagement by the weft detecting mechanism as the transerrer 16 thereafter moves downward.

40 45 Such engagement is shown in Fig. 3 in which it is assumed that the weft carrier *W* is substantially exhausted, and has caused movement of the rod 19 to the operative position shown in Fig. 7. The feed pawl 20 rests against the shield 24.

The next succeeding upward movement 50 of the transerrer places the parts in the position shown in Fig. 4 where it will be seen that the feed pawl 20 again engages the tooth *c* of the ratchet wheel 12, as in Fig. 1, but that the shield 24 has been moved by engagement of the pin 19 with the cam portion 29 (Fig. 8) so that the tooth *d* is no longer covered by the shield. The relation 55 of the parts is such, however, that the tooth *d* is not uncovered until the feed pawl 20 has passed above the point of the tooth *d* in its upward movement.

The parts are shown in Fig. 5 in the po-

sition which they assume on the next downward movement of the transerrer after indication of weft exhaustion, the weft detecting mechanism then engaging the weft carrier *W'* in the second shuttle *S'*. The mechanism for alternately presenting two different shuttles is not shown in the drawings but comprises well-known drop box mechanism which constitutes no part of my present invention. One form of mechanism suitable for the purpose is shown in the 75 prior patent to Marco, No. 914,739 issued March 9, 1909. This weft carrier *W'* is assumed in Fig. 4 to have a sufficient supply of weft thereon. During this downward movement the rod 19 is engaged by the cam projection 30 on the arm 28 and is reset in inoperative position by such engagement.

In Fig. 6 the parts are shown in mid position during the next upward movement of the transerrer, the feed pawl 20 engaging the tooth *d* of the ratchet wheel 12 and being about to advance the weft carrier *W'* in the magazine to the transfer position indicated in dotted lines in Fig. 6. As the magazine is fed forward the shield 24 mounted frictionally thereon moves therewith and protects the tooth *e* of the ratchet wheel 12. The parts are thus restored to normal operative position with the holding pawl 13 engaging the tooth *b* instead of the tooth *a*.

If the weft carrier *W'* should be found substantially exhausted when the parts are in the position shown in Fig. 5, the pin 19 will be again moved to the left in Fig. 7 and during the feeding operation shown in Fig. 6, the pin will move the shield 24 to uncover the tooth *e*, so that a second advance of the magazine will occur on the next upward movement of the transerrer following the movement of Fig. 6.

I have thus provided feeding mechanism by which the advance of a fresh weft carrier to transfer position is delayed so that transfer can only occur on the fourth pick 100 after indication of substantial weft exhaustion, and I have also provided mechanism permitting substantial weft exhaustion in two shuttles to be successively and independently indicated.

The counter weight 27 is provided to prevent displacement of the shield 24 during the relatively long period between weft carrier transfers, when the continued jar of the machine might displace the parts if dependence were placed on friction alone to hold the shield in position. With the counter weight in use, only upward displacement of the shield is possible and such movement is limited by engagement of the arm 31 110 with the stud 32 (Fig. 1) on the holding pawl 13.

Certain features of my invention are not

limited in their utility to the rotary type of weft carrier magazine.

Having thus described my invention, it will be evident that changes and modifications can be made therein by those skilled in the art within the spirit and scope of my invention as set forth in the claims, and I do not wish to be otherwise limited to the details herein disclosed, but what I claim is:—

10 1. In a loom, in combination, a rotary magazine, a transferrer having a transferring movement at each alternate beat of the lay, feeding means associated with said transferrer effective to advance the magazine angularly after indication of substantial weft exhaustion, and means to delay the operation of said feeding means.

2. In a loom, in combination, a rotary magazine, a transferrer having a transferring movement at each alternate beat of the lay, and means associated with said transferrer effective to advance the magazine after indication of substantial weft exhaustion, said means becoming operative only 25 on the second upward movement of said transferrer after such indication.

3. In a loom having two shuttles each given two picks alternately, in combination, a rotary magazine, means to feed said magazine after indication of substantial weft exhaustion, and a device effective to delay the operation of said feeding means so that transfer will occur only on the return of the indicated shuttle.

35 4. In a loom having two shuttles each given two picks alternately, in combination, a rotary magazine, a transferrer having a transferring movement at each alternate beat of the lay, and means to delay weft carrier transfer after indication of substantial weft exhaustion until the substantially exhausted shuttle returns to transfer position.

5. In a loom, a rotary magazine, a transferrer movable on alternate picks to determine substantial weft exhaustion, and means to feed said magazine to present a fresh weft carrier in transfer position after the next succeeding actuation of the transferrer following indication of substantial weft exhaustion, said weft carrier being thereafter transferred on the second actuation of said transferrer following indication of substantial weft exhaustion.

55 6. In a loom having two shuttles each giving two picks alternately, in combination, a rotary magazine, a transferrer having a transferring movement at each alternate beat of the lay, and means to delay weft carrier transfer after indication of substantial weft exhaustion until the substantially exhausted shuttle returns to transfer position, said means being also effective to similarly delay transfer to the second shuttle if sub-

stantial weft exhaustion thereof is indicated 65 before the first shuttle is replenished.

7. In a loom, in combination, a rotary magazine having a ratchet wheel, a transferrer actuated on each alternate beat of the lay, a feed pawl for said ratchet wheel moved with said transferrer, a device effective to maintain said feed pawl normally inoperative, and means to move said device after indication of substantial weft exhaustion, thereby permitting said feed pawl to 75 advance said magazine.

8. In a loom, a rotary magazine having a ratchet wheel, a transferrer movable on alternate picks to determine substantial weft exhaustion, a feed pawl for said ratchet 80 wheel moved with said transferrer, and means to control the operation of said feed pawl to render the pawl inoperative only after the next downward movement of the transferrer following indication of substantial weft exhaustion.

9. In a loom, in combination, a rotary magazine having a ratchet wheel, a transferrer, a feed pawl mounted on said transferrer, a shield normally rendering said feed 90 pawl inoperative, and means to withdraw said shield after indication of substantial weft exhaustion.

10. In a loom, in combination, a rotary magazine having a ratchet wheel, a regularly actuated transferrer, a feed pawl for said ratchet wheel mounted on the transferrer, a shield for said ratchet wheel, and means on the transferrer effective to engage and move said shield after indication of substantial weft exhaustion, thereby rendering 95 said feed pawl operative.

11. In a loom, in combination, a rotary magazine having a ratchet wheel, a regularly actuated transferrer, a feed pawl for 105 said ratchet wheel, a shield for said feed pawl mounted on the magazine and frictionally engaging the same, and means on the transferrer effective to engage and move said shield against the friction on indication of substantial weft exhaustion, thereby rendering 110 said feed pawl operative.

12. In a loom, in combination, a rotary magazine having a ratchet wheel, a regularly actuated transferrer, a feed pawl for 115 said ratchet wheel, a shield for said feed pawl mounted on the magazine and frictionally engaging the same, means on the transferrer effective to engage and move said shield against the friction on indication of substantial weft exhaustion, thereby rendering 120 said feed pawl operative, a stop for said shield and a counter weight associated with said shield acting to move said shield against said stop.

13. In a loom, in combination, a rotary magazine having a ratchet wheel, a regularly actuated transferrer, a feed pawl for 125

said ratchet wheel, a shield for said feed pawl, a stop for said shield, means to move said shield positively away from said stop, and means to prevent accidental movement 5 of said shield away from said stop.

14. In a loom, in combination, a weft carrier magazine, weft detecting mechanism, means to feed a weft carrier forward to transfer position after indication of sub-

stantial weft exhaustion, and a device effective to delay the operation of said feeding means so that normal transfer will occur only on the fourth pick of the loom after indication.

In testimony whereof I have hereunto 15 affixed my signature.

EPPA H. RYON.
